UNITED STATES PATENT OFFICE

102,487

DESIGN FOR HOSIERY

Louis H. Mendelsohn, Paterson, N. J.

Application June 6, 1936, Serial No. 63,051

Term of patent 14 years

To all whom it may concern:

Be it known that I, Louis H. Mendelsohn, a citizen of the United States, residing at Paterson, in the county of Passaic and State of New Jersey, have invented a new, original, and ornamental Design for Hosiery, of which the following is a specification, reference being had to the accompanying drawing, forming part thereof.

Fig. 1 is a front elevation of a stocking, showing my new design;

Fig. 2 is a side elevation thereof.

In the drawing, the lines on the upper toe portion of the stocking provide a design comprising a plurality of diamond shape openings arranged as illustrated, with a stripe of similar openings adjacent the upper border of the main group.

I claim:

The ornamental design for hosiery as shown and described.

LOUIS H. MENDELSON.
